UNITED STATES PATENT OFFICE.

JOSEPH RIEPP, OF NEW YORK, N. Y.

LIQUID-MEASURING TANK.

1,015,636.

Specification of Letters Patent. Patented Jan. 23, 1912.

Application filed May 16, 1911. Serial No. 627,423.

To all whom it may concern:

Be it known that I, JOSEPH RIEPP, a citizen of the United States, residing at New York, in the county of New York and State of New York, have invented new and useful Improvements in Liquid-Measuring Tanks, of which the following is a specification.

The invention relates to tanks, and more particularly to the class of liquid measuring tanks.

The primary object of the invention is the provision of a tank in which liquid, for instance milk or cream, may be measured in predetermined quantities when being dispensed from the said tank, the tank being provided with an inner receptacle for holding the liquid, thereby forming an ice receiving chamber or space between the same and the tank, thus enabling the contents of the receptacle to be maintained cool.

Another object of the invention is the provision of a tank in which the outer casing thereof is provided with an air space, the tank being adapted to receive ice or other cooling medium for maintaining the contents stored within said tank cool, the storage reservoir or receptacle being removable from the tank, whereby it may be cleaned for sanitary purposes.

A further object of the invention is the provision of a measuring tank of this character which is simple in construction, thoroughly reliable and efficient in its purpose, and inexpensive in manufacture.

With these and other objects in view, the invention consists in the construction, combination and arrangement of parts, as will be hereinafter more fully described, illustrated in the accompanying drawings, and pointed out in the claims hereunto appended.

In the drawings: Figure 1 is a perspective view of a measuring tank constructed in accordance with the invention. Fig. 2 is a vertical longitudinal sectional view through the same. Fig. 3 is a horizontal transverse sectional view. Fig. 4 is a perspective view of the valve and the valve seat therefor. Fig. 5 is a vertical transverse sectional view through the tank. Fig. 6 is a fragmentary perspective view of

one of the supporting brackets for the reservoir, the same being shown in position on the tank.

Similar reference characters indicate corresponding parts throughout the several views of the drawings.

Referring to the drawings by numerals, 60 the measuring tank comprises an outer casing 5 supported upon legs 6, and is formed with an inner lining 7, the same being spaced from the sides and bottom of the casing to form an air chamber or cell 8 entirely about the sides and bottom of the said casing. This lining 7 also provides an ice compartment or chamber 9 interiorly of the casing, in which is removably held a liquid receptacle or reservoir, presently described.

The liquid reservoir or chamber comprises a cylindrical body 10, the same being contracted at opposite ends, and into which is adapted to be introduced liquid, for instance, milk or cream, for the dispensing thereof in predetermined quantities. At the upper contracted end of the body 10 is formed a circular flange 11, in which telescopes a removable cap or lid 12 which is readily removable to permit the introduction of liquid into the reservoir or receptacle. Spaced from the forwardly inclined bottom 13 of the lower contracted end of the body 10 is an auxiliary bottom 14; providing a lower measuring compartment 15, the same being divided by means of a vertical partition 16, medially thereof, into independent measuring cells or chambers 17, the liquid being let into the latter from the body 10, as will be presently described.

Formed in the auxiliary bottom 14 is an opening 18, the wall of which serves as a valve seat 19, in which is normally engaged a valve or plug 20, the opening being provided with a spider 21 integral with the valve seat 19, and rising centrally from the spider is a guide rod 22 which is extended vertically upwardly through the body 10, and has telescoping thereon a valve stem 23, 100 the same having fixed to its lower end the valve or plug 20, the valve stem 23 being adapted to work through a suitable opening 24 formed in the cap or lid 12, and has loose connection with a rocking lever 25 105 fulcrumed in a post or standard 26 fixed to

and rising from a removable cover 27 fitted on the top edge of the casing 5, the cover 27 being provided with a suitable opening alining with the opening 24 and receiving 5 the stem 23.

Suitably fixed to the lining 7 in the casing 5, spaced from the bottom thereof, are diametrically opposed brackets 28, the same being formed with upturned bearings 29 10 engaging in an annular groove 30 formed in the auxiliary bottom 14 of the body 10, the brackets being designed to support the said body within the casing 5 spaced from the lining 7, so that ice may be packed about 15 the body and underneath the contracted lower end thereof, the upturned bearings 29 of the brackets being adapted to prevent the displacement of the body 10, when supported thereby.

20 Formed on or secured to the side wall of the contracted lower end of the body, and leading from the respective chambers or cells 17 therein, are discharge tubes 31, the same being projected through suitable alining openings formed in the lining 7 and casing 5, at the front thereof, the tubes 31 being formed with abutment rings 32, between which and the lining 7 are interposed resilient gaskets 33, so that when the 25 latter are compressed therebetween, there will be no possibility of leakage about the tubes from the chamber 9 in the casing. These tubes 31, at their outer ends, are exteriorly threaded for the mounting of faucets 34 thereon, the latter being adapted 30 to be worked home on the tubes sufficiently to compress the gaskets 33 between the rings 32 and the lining 7, thus preventing leakage from the ice chamber 9 into the casing. 35 The faucets 34 being of the ordinary well-known construction, and permit the drawing off of liquid contained in the measuring chambers or cells 17 in the bottom or lower contracted end of the body 10, it being understood, of course, that the valve 20 will 40 be opened and closed to regulate the supply of liquid from the body to the measuring chambers.

45 Leading from the bottom of the ice chamber 9 and extending through the bottom of the casing 5 is a drain cock 35 which permits the draining of water from the said chamber 9 when the ice melts therein.

The bottom of the casing is provided with 50 a suitable port or opening which is closed by a slide 36, the latter being mounted upon the bottom of the casing 5 in any suitable manner, and permits access to be had through the port to the air space between the casing 5 and the lining 7 therein.

55 The outer end of the lever 25 has connected therewith a suitable pull chain or cord 37 which permits the convenient raising of the valve or plug 20 interiorly of the body for establishing communication be-

tween the latter and the measuring cells or chambers 17 in the contracted bottom thereof.

On the removal of the faucets 34 from the discharge tubes 31, the body 10 may be readily taken out of the ice chamber 9 for the convenient cleaning of both the latter and the said body, it being understood, of course, that the cover 27 and also the lid 12 are removed from the casing and body to permit the latter to be taken from the said casing.

Formed on the valve stem 23 spaced above the valve 20 is a perforated agitator disk 38 which enables the agitation of the contents of the body 10 on the lifting of the 80 valve from its seat.

What is claimed is:

1. A measuring device of the class described, comprising a casing having an air cell extending about the sides and bottom 85 thereof, and also an ice chamber therein, the air cell being formed between the latter and the casing, brackets projecting inwardly from opposite sides of the chamber, a reservoir supported upon said brackets and having independent measuring cells in its bottom, discharge tubes carried by the reservoir and projecting through the casing exteriorly thereof to permit the delivery therefrom of the contents of the measuring cells, an auxiliary bottom formed in the reservoir spaced 90 from the lower end thereof and having a valve seat opening therein, a valve normally closing said opening, and means for raising and lowering the valve.

2. A measuring device of the class described, comprising a casing having an air cell extending about the sides and bottom thereof and also an ice chamber therein, the air cell being formed between the latter and the casing, brackets projecting inwardly from opposite sides of the chamber, a reservoir supported upon said brackets and having independent measuring cells in its bottom, discharge tubes carried by the reservoir 105 and projecting through the casing exteriorly thereof to permit the delivery therefrom of the contents of the measuring cells, an auxiliary bottom formed in the reservoir spaced from the lower end thereof and having a 110 valve seat opening therein, a valve normally closing said opening, means for raising and lowering the valve, abutment rings formed on the discharge tubes, and gaskets interposed between the abutment rings and the 115 casing for forming tight joints therebetween.

3. A measuring device of the class described, comprising a casing having an air cell extending about the sides and bottom 125 thereof and also an ice chamber therein, the air cell being formed between the latter and the casing, brackets projecting inwardly from opposite sides of the chamber, a reservoir supported upon said brackets and hav-

- ing independent measuring cells in its bottom, discharge tubes carried by the reservoir and projecting through the casing exteriorly thereof to permit the delivery therefrom of the contents of the measuring cells, an auxiliary bottom formed in the reservoir spaced from the lower end thereof and having a valve seat opening therein, a valve normally closing said opening, means for raising and lowering the valve, abutment rings formed on the discharge tubes, gaskets interposed between the abutment rings and the casing for forming tight joints therebetween, and faucets threaded on the outer ends of the said discharge tubes for compressing the gaskets between the casing and the abutment rings. 5
4. A measuring device of the class described, comprising a casing having an air cell extending about the sides and bottom thereof and also an ice chamber therein, the air cell being formed between the latter and the casing, brackets projecting inwardly from opposite sides of the chamber, a reservoir supported upon said brackets and having independent measuring cells in its bottom, discharge tubes carried by the reservoir and projecting through the casing exteriorly thereof to permit the delivery therefrom of the contents of the measuring cells, an auxiliary bottom formed in the reservoir spaced from the lower end thereof and having a valve seat opening therein, a valve normally closing said opening, means for raising and lowering the valve, abutment rings formed on the discharge tubes, gaskets interposed between the abutment rings and the casing for forming tight joints therebetween, faucets threaded on the outer ends of the said discharge tubes for compressing the gaskets between the casing and the abutment rings, a spider spanning the opening in the auxiliary bottom in the reservoir, a guide rod rising from said spider, a valve stem connected with the valve and surrounding the said guide rod, and removable lids closing the top of the casing and reservoir, respectively. 10
5. A measuring device of the class described, comprising a casing having an air cell extending about the sides and bottom thereof and also an ice chamber therein, the air cell being formed between the latter and the casing, brackets projecting inwardly from opposite sides of the chamber, a reservoir supported upon said brackets and having independent measuring cells in its bottom, discharge tubes carried by the reservoir and projecting through the casing exteriorly thereof to permit the delivery therefrom of the contents of the measuring cells, an auxiliary bottom formed in the reservoir spaced from the lower end thereof and having a valve seat opening therein, a valve normally closing said opening, means for raising and lowering the valve, abutment rings formed on the discharge tubes, gaskets interposed between the abutment rings and the casing for forming tight joints therebetween, faucets threaded on the outer ends of the said discharge tubes for compressing the gaskets between the casing and the abutment rings, a spider spanning the opening in the auxiliary bottom in the reservoir, a guide rod rising from said spider, a valve stem connected with the valve and surrounding the said guide rod, and removable lids closing the top of the casing and reservoir, respectively. 15
- In testimony whereof I affix my signature in presence of two witnesses.
